Des. 241,559

Patented Sept. 21, 1976

241,559

PROFESSIONAL EBULLIOSCOPE

Robert Rakowski, 3411 Rosalie Ave.,
Baltimore, Md. 21234

Filed Apr. 9, 1975, Ser. No. 566,409

Term of patent 14 years

Int. Cl. D24—02

U.S. Cl. D32—1 R

FIG. 1.

FIG. 2.

FIG. 3.

FIG. 4. FIG. 5.

FIG. 1 is a side elevational view of my new design of a professional ebullioscope;

FIG. 2 is another elevational view partly in cross-section and partly broken away for clarity viewed from the right side of FIG. 1;

FIG. 3 is a reduced scale perspective view of my new design shown associated with environmental apparatus illustrated in broken lines;

FIG. 4 is a top planed view of my new design represented on the same scale as FIGS. 1 and 2; and

FIG. 5 is a bottom planed view thereof.

The broken lines are shown for illustrative purposes only.

I claim:

The ornamental design for a professional ebullioscope, as shown and described.
